UNITED STATES PATENT OFFICE.

FRANK P. BARNEY, OF CHARTLEY, MASSACHUSETTS, ASSIGNOR TO JOSEPH H. TIDD
AND WINTHROP L. TIDD, OF TAUNTON, MASSACHUSETTS, COPARTNERS.

COLLAR-BUTTON.

997,948.

Specification of Letters Patent. Patented July 18, 1911.

Application filed October 29, 1910. Serial No. 589,684.

To all whom it may concern:

Be it known that I, FRANK P. BARNEY, a citizen of the United States, residing at Chartley, in the county of Bristol and State 5 of Massachusetts, have invented certain new and useful Improvements in Collar-Buttons, of which the following is a specification.

This invention relates to collar-buttons, 10 and it consists in the novel construction and combination of parts comprising the same, all as more fully hereinafter set forth and claimed.

The object of the invention is to produce 15 an improved collar-button of the non-separable, jointless or hingeless and solderless type.

The improved button, being the subject of 20 this application for patent, is strong and light and inexpensive to manufacture, and having its shank portion or post formed from a staple-like member rigidly secured to and connecting the front and back heads of the button.

25 In the accompanying sheet of drawings, Figure 1 represents a front elevation of my improved collar-button. Fig. 2 is a corresponding side view. Figs. 3 and 4 are horizontal sectional views, taken on lines 3 3 and 30 4 4 of Fig. 1. Fig. 5 is a plan view of the back disk used in the front head. Fig. 6 is a transverse sectional view of the front head's shoe or cap. Fig. 7 is a similar view of the back head's shoe. Fig. 8 is a plan view 35 of the inner disk used in connection with the post and back head. Fig. 9 is a sectional view of the same, taken on line 9 9 of Fig. 8. Fig. 10 is a plan view of the outer disk, adapted to be superimposed upon said inner disk. Fig. 11 is a perspective view of 40 the unbent blank from which the post is formed; and Fig. 12 is a vertical sectional view, taken substantially on line 12 12 of Fig. 2.

45 My improved collar-button A consists in general of the front head a, the back head b, and the bifurcated post c, all formed from suitable thin sheet metal stock.

The post c is or may be produced from 50 the relatively thick, flat blank member m, shown in Fig. 11; the same, when bent, having a staple-like form; its two laterally separated legs extend downward at substantially right angles from the center connecting tie or arch c¹ (Fig. 12) and terminate

each in oppositely disposed lugs c², thus forming a T-shaped end. The legs may be slightly inclined or curved outwardly, thereby correspondingly increasing the distance between them, substantially as shown. The 60 upper or front head a (Fig. 12) consists of the outer, cup-shaped shoe d, having the arch portion c¹ of the post c seated therein, and the thin, flat disk e, constituting the under side of the head, having oppositely 65 cut notches e¹ in its edge, adapted to snugly receive the post's legs. As thus arranged, the arch portion of the post lies between the adjacent surfaces of the front shoe d and disk e; all being firmly secured together 70 by turning or rolling over the side walls of the shoe—see Figs. 3 and 12.

The bottom or back head b is usually somewhat larger than the front head; its construction, however, is substantially the 75 same as the latter. It consists of the outer, cup-shaped shoe f, a disk h seated therein, provided with notches h¹, constructed to receive and laterally position the lower or 80 T-shaped end portions of the post's legs, and a cover or cap disk i superimposed upon disk h, having openings i¹ through which the legs extend. The openings i¹ of the cap-disk i are elongated, each being adapted to receive therethrough the respective up-swaged portion of the disk h and also the 85 corresponding leg of the post; all as clearly shown in Figs. 4 and 12. After the said members of the head b are thus assembled the side walls of the shoe f are rolled over in a 90 well-known way, thereby rigidly securing the parts together—see Figs. 4 and 12. It may be stated that the presence of the disk i materially strengthens the head b, while at 95 the same time practically concealing the notches of the disk h, thereby, too, giving to the button a more attractive and finished effect. The stock or metal at the inner or bottom end of each notch h¹ of disk h is un-swaged to form transverse recesses or seats 100 h² on its underside, adapted to receive the said bottom lugs c² of the post's legs. The form and size of the seats cross-sectionally are substantially the same as the counter-part members or lugs.

105 What I claim as my improvement and desire to secure by U. S. Letters Patent is:—

1. The improved non-separable, hingeless and solderless collar-button herein described, 110 the same consisting in the combination of a

front shoe member, a one-piece post member comprising a pair of legs having their lower ends provided with lateral lugs, and an enlarged head or tie-plate interposed between 5 and connecting the opposite ends of the legs, the tie-plate being located in said shoe, a notched disk having the adjacent portion of the post's legs disposed therein, the said connecting portion of the post being located 10 between the adjacent faces of the shoe and notched disk, all being rigidly secured together by inturning the outer edge of the front or upper shoe, a bottom shoe, a disk positioned therein provided with sockets 15 having the lugs of the post legs mounted therein, and means coöperating with the bottom shoe and its disk for rigidly securing the said shoe, disk and post legs together.

2. In a collar-button, the combination 20 with front and back shoes and front and

back disks disposed in the respective shoes, of a one-piece post member consisting of a pair of laterally separated legs having a tie-plate connecting them at the upper end, the tie-plate being located between said front 25 shoe and its disk and rigidly secured to them, lugs integral with the lower end of the legs positioned between the said back shoe and back disk and interlocking with the latter, an apertured cap-disk superimposed 30 upon the back disk having the post legs extending through the disks, and means co-operating with the bottom shoe and its disks for rigidly securing them to the post legs.

In testimony whereof I have affixed my 35 signature in presence of two witnesses.

FRANK P. BARNEY.
